CLAIM

The ornamental design for a PICC saddle device, as shown and described.

DESCRIPTION

FIG. 1 is an exploded isometric view of the PICC saddle device (also shown in broken line are a body part to which the PICC saddle device may be attached, and a peripherally-inserted central catheter (PICC) system which may be housed within the PICC saddle device);

FIG. 2 is a front elevation view of the PICC saddle device;

FIG. 3 is a plan view of the PICC saddle device;

FIG. 4 is a bottom view of the PICC saddle device;

FIG. 5 is a rear elevation view of the PICC saddle device; and,

FIG. 6 is a side elevation view of the PICC saddle device.

The broken line showing is included for the purpose of illustrating portions of the article and forms no part of the claimed design.
